(57) **CLAIM**

The ornamental design for an ice making water dispenser, as shown and described.

DESCRIPTION

FIG. 1 is a perspective view of an ice making water dispenser showing the new design.

FIG. 2 is another perspective view of the ice making water dispenser of FIG. 1.

FIG. 3 is a further perspective view of the ice making water dispenser of FIG. 1.

FIG. 4 is a front view of the ice making water dispenser of FIG. 1.

FIG. 5 is a rear view of the ice making water dispenser of FIG. 1.

FIG. 6 is a side view of the ice making water dispenser of FIG. 1.

FIG. 7 is an opposite side view the ice making water dispenser of FIG. 1.

FIG. 8 is a top view the ice making water dispenser of FIG. 1; and,

FIG. 9 is a bottom view the ice making water dispenser of FIG. 1.
